(57) **CLAIM**

The ornamental design for a combined locking lug nut and key, as shown and described.

DESCRIPTION

FIG. 1 is a front view of a lug nut key showing my new design, shown separately for clarity of illustration.

FIG. 2 is a rear view of the lug nut key shown in FIG. 1.
FIG. 3 is a left side view of the lug nut key shown in FIG. 1.

FIG. 4 is a right side view of the lug nut key shown in FIG. 1.

FIG. 5 is a top view of the lug nut key shown in FIG. 1.
FIG. 6 is a bottom view of the lug nut key shown in FIG. 1.
FIG. 7 is a top and left side perspective view of the lug nut key shown in FIG. 1.

FIG. 8 is an exploded top and left side perspective view of the combined locking lug nut and key showing my new design.

FIG. 9 is a front view of the lug nut shown in FIG. 8, shown separately for clarity of illustration.

FIG. 10 is a rear view of the lug nut shown in FIG. 8.

FIG. 11 is a left side view of the lug nut shown in FIG. 8.

FIG. 12 is a right side view of the lug nut shown in FIG. 8.

FIG. 13 is a top view of the lug nut shown in FIG. 8.

FIG. 14 is a bottom view of the lug nut shown in FIG. 8; and,

FIG. 15 is a top and left side perspective view of the lug nut shown in FIG. 8.
